UNITED STATES PATENT OFFICE.

JACOB A. STEIN, OF NEW YORK, N. Y.

BOX FOR PLUMES AND SIMILAR ARTICLES.

1,075,446.

Specification of Letters Patent.

Patented Oct. 14, 1913.

Application filed June 21, 1912. Serial No. 704,981.

To all whom it may concern:

Be it known that I, JACOB A. STEIN, a citizen of the United States, residing at New York city, county and State of New York, have invented a new and Improved Box for Plumes and Similar Articles, of which the following is a specification.

This invention relates to a novel box for holding plumes and similar articles which is so constructed that with the employment of but a minimum number of parts, the plumes are securely held in position during shipment, etc., while they may be readily inserted into or withdrawn from the box whenever so desired.

In the accompanying drawing: Figure 1 is a longitudinal section through a box embodying my invention; Fig. 2 a perspective view partly in section thereof, and Fig. 3 an enlarged cross section on line 3—3, Fig. 2.

The box is preferably made of card board or similar material and consists essentially of a bottom 10, side walls 11 which are integral with said bottom, and separate end walls 12 interposed between the side walls. Along their upper edges, the side and end walls are shown to be reinforced as at 13, all of the parts 10, 11, 12, 13 being provided with a suitable covering 14. To increase the stability of the box, the separate end plates 12 are furnished with bottom flaps, one of which, say flap 15 is glued or otherwise firmly secured to bottom 10, while the other flap 16 is shown to be made somewhat longer than flap 15 and has the additional function of holding the plumes 17 in position. Flap 16 is covered at its top and bottom with a strip 18 of cloth or similar reinforcing material which also extends over the edge of said flap. The latter is secured to bottom 10 by means of a number of rivets

or other fastening means 19, as clearly illustrated in Figs. 2 and 3. Rivets 19 are so spaced from each other that a pocket 20 is formed between each pair of adjoining rivets, said pockets serving for the reception of the plume stems 21. Flap 16 is made of transversely corrugated shape, one corrugation being formed between each pair of adjoining rivets 19 (Fig. 2), so that in this way each pocket 20 is normally open to an extent sufficient to receive a plume stem.

It will be seen that by the construction described, the plume stems may be readily inserted into the pockets 20 to be frictionally engaged by the parts 10 and 16, so that the plumes are securely held in position. In this way the latter are prevented from being soiled or otherwise damaged during shipment, etc., while they may be readily removed from the box for displaying or other purposes whenever so desired. This result is obtained with the use of but a minimum number of parts, the reinforcing bottom flap of one of the end walls being utilized for forming the stem receiving pockets without in any wise impairing the reinforcing effect of said flap.

I claim:

A box of the character described, provided with a bottom, an end wall having a flap that overlies the bottom and is provided with a plurality of transverse corrugations, and fasteners that secure said flap to said bottom intermediate said corrugations, whereby a series of normally open, plume-stem receiving pockets is formed between said bottom and flap.

JACOB A. STEIN.
